UNITED STATES PATENT OFFICE.

EDWARD J. DE SMEDT, OF WASHINGTON, DISTRICT OF COLUMBIA.

APPARATUS FOR REFINING ASPHALTUM FOR PAVING, &c.

SPECIFICATION forming part of Letters Patent No. 292,417, dated January 22, 1884.

Application filed December 28, 1883. (No model.)

To all whom it may concern:

Be it known that I, EDWARD J. DE SMEDT, of Washington city, in the District of Columbia, have invented a certain new and useful

5 Improvement in Apparatus for Refining Asphaltum for Paving and other Purposes, of which the following is a specification.

My invention has relation to the improvement in refining asphaltum for paving and 10 other purposes for which I have already received Letters Patent dated October 9, 1883, and numbered 286,396; and its object is to obtain an economical and efficient arrangement of apparatus for carrying out said patented 15 process.

The nature of my improvement and the manner in which I carry it into practical effect will be readily understood by reference to the accompanying drawings, in which—

20 Figure 1 is a sectional view of so much of the apparatus as needed for the purpose of explanation. Fig. 2 is an enlarged sectional view of the steam-ejector used to exhaust the fumes of gases from the kettles.

25 A is one of a number of furnaces containing one or more melting-kettles, B, for receiving the asphaltum to be refined. The kettle is provided with a cover, a, from the top of which leads a pipe, b, which by pipe d d communicates with the fire box or chamber of the special furnace F, said pipe discharging into the said furnace through the tuyere y.

In practice, as just above intimated, there are a large number of melting-kettles—usually 35 sixteen or more—all of which discharge their fumes or gases into the special furnace F through their own system of pipes, &c. The discharge-tuyeres of these kettles are indicated at y.

40 The description of the connections, &c., of the kettle B, with its furnace A and the special furnaces F, will answer for all the other kettles, the general arrangement of the plant being substantially like that represented in 45 Fig. 1 of the drawings annexed to my said patent hereinbefore referred to. Pipe d is provided with a controlling cock or valve, g, and also with a steam jet or nozzle, e', which enters the pipe at the elbow d', as indicated 50 plainly in Fig. 3. Under this arrangement

the steam-jet acts on the principle of an ejector, exhausting the fumes and gases from the kettle and forcing them along into furnace F, where they are burned.

It becomes a desideratum, particularly with 55 a large number of kettles, each of which must have its own ejector or set of ejectors, to provide means whereby steam can be generated and supplied conveniently, economically, and efficiently to the ejectors, at the same time bringing the apparatus or plant within as small compass as possible. To this end I combine with the special furnace F a steam-boiler, G, which is heated by that furnace, and with the steam-space of which the steam-supply pipes of the 60 several ejectors e' are in communication, as indicated in the drawings, where o is a circular steam-supply pipe communicating with and taking its supply of steam from the steam-space of boiler G, and e' is a branch pipe (controlled by valve h') leading from o to the ejector e'. Thus the steam supplied to the ejectors, whereby the noxious fumes and vapors are exhausted from the kettles, is generated by the 65 heat evolved in the furnace F, in which those 70 fumes and vapors are consumed.

It may be desired at times to divert the exhausted gases, &c., taken from any one or more of the kettles into the furnace A of that kettle, instead of into the special furnace F. 80 To this end I lead from the abductor-pipe b of each kettle a pipe, c, (separate and distinct from pipe d,) which enters the fire-box of its furnace A. Pipe c has a controlling-cock, f, and is provided with an ejector, e, (similar to 85 e') which in like manner draws its supply of steam from boiler G, and is controlled by a valve, h. This system of pipes, however, may be dispensed with, if desired.

Having described my improvement, what I 90 claim, and desire to secure by Letters Patent, is—

1. The combination, with a number of covered melting-kettles and furnaces for heating the same, of the separate special furnace F, 95 the steam-boiler G, heated by the same, conduit d, leading from each kettle to the furnace F, and the ejector e', drawing its supply of steam from said boiler and acting to exhaust the fumes and gases from the kettle 100

through said pipe *d* into furnace *F*, as and for the purposes hereinbefore set forth. 2. The combination of the covered kettles *B*, furnaces *A*, special furnace *F*, boiler *G*, pipes *d* *c*, ejectors *e* *c*, connected with and taking their steam from boiler *G*, and valves or cocks for controlling the steam-supply, and for directing the abducted fumes or gas into either pipes *d* or *c* at will, the whole arranged and

adapted to operate as and for the purposes to hereinbefore set forth.

In testimony whereof I have hereunto set my hand this 21st day of December, 1883.

E. J. DE SMEDT.
